UNITED STATES PATENT OFFICE.

BENJAMIN G. WATKINS, WALTER P. WATKINS, AND TAYLOR WATKINS, OF ELIZABETHTOWN, KENTUCKY.

POST-HOLE AUGER.

1,110,517.

Specification of Letters Patent. Patented Sept. 15, 1914.

Application filed May 17, 1912. Serial No. 698,020.

To all whom it may concern:

Be it known that we, BENJAMIN G. WATKINS, WALTER P. WATKINS, and TAYLOR WATKINS, citizens of the United States, and residents of Elizabethtown, in the county of Hardin and State of Kentucky, have invented certain new and useful Improvements in Post-Hole Augers, of which the following is a specification, reference being had to the accompanying drawings.

This invention has relation to certain new and useful improvements in earth augers.

Our invention has for its object to improve the construction of that class of augers which are employed in boring post holes.

To this end the invention consists in constructing a semi-cylindrical sheet metal member which is provided with a pointed curved cutting blade, and an earth carrying flange, the auger being especially adapted to be used in soggy clinging earth.

With these and other objects in view, the present invention consists in the combination and arrangement of parts as will be hereinafter more fully described and finally pointed out in the appended claims, it being further understood that changes in the specific structure shown and described may be made within the scope of the claims without departing from the spirit of the invention.

In the accompanying drawings forming a part of this specification and in which like numerals of reference indicate similar parts in the several views: Figure 1, is an elevational view with parts broken away of an earth auger embodying our invention. Figs. 2 and 3, are elevational views of the auger head, disclosing opposite edges of the same.

Fig. 4 is a section on line 4, 4 of Fig. 1.

In our present invention we provide an earth auger especially adapted to be used in wet, soggy and clinging soil, as well as in extremely hard earth, in that, as the hole is bored water is introduced, this resulting in the earth clinging to the auger. In emptying the auger it is simply necessary to lightly tap the same in order to remove the collected material.

In the drawings the numeral 1, designates a sheet metal cylindrical member preferably including a cylinder of approximately $\frac{1}{2}$ of a circle, so that there is formed a lengthwise running opening between the auger edges 2 and 3, of approximately 144 degrees.

As clearly shown in Figs. 2 and 4, the lower portion 4, of the longitudinal edge 3, is sharpened, and bulged outward. This is necessary in order that the auger will bore a hole slightly larger than its main diameter, to facilitate the removal of the auger from the hole. At the edge 4, and lower end the member is continued in the acute angled or sector-shaped inwardly curved or dished cutter blade 5, the point 6, of which is blunt and ends at a point marking the center of the cylinder 1, as shown in Fig. 1. From the opposite longitudinal edge and corner 7, as shown in Fig. 1, extends obliquely the inwardly directed flange 9, having its edge 10, sharpened. As disclosed in Fig. 4, this flange is of decreasing width the end *x*, being wider than the end *y*. An escape opening is formed between the end *y* and the dished cutter 5, and the bulging 4, is formed at union of the edge with a cutter blade.

Secured to the upper edge of the auger, is a spanner 12, having a threaded handle sockets 13, and the apertured ends 14, which by means of the rivets 15, are secured at diametrically opposite points to the head 1. Secured within the socket 13, is the pipe 16, having the head 18, giving support to the operating handle 17.

As explained, the auger is especially adapted to be used in moist earth. The blade 5, cuts the soil, which as the auger works downward, rides upward over the flange 9. Being moist the earth clings to the inner surface of the auger head and is carried thereby. When a suitable amount of earth has been collected within the auger head the tool is removed from the hole and slightly tapped when the clinging earth readily slips out of the auger head. In advancing, the auger makes a smooth round hole. All stones as they are dislodged, roll over the blade 5, without interfering with the operation of the tool. The stones are manually removed after the auger is withdrawn, though the smaller stones will of course be carried up and be contained by the clinging soil.

Where the earth is particularly hard and stony the point marking the location of the post hole is moistened, then as the auger is advanced in the earth water is introduced into the opening resulting in the earth at the bottom being moistened so that the same can be readily removed.

It is of course understood that augers embodying our invention may be made of various sizes.

The tool is simple and inexpensive in construction and both durable and efficient in operation and enable an operator to bore a post hole of any suitable size and depth, with ease, accuracy and despatch.

Having thus described our said invention, what we claim as new and desire to secure by United States Letters Patent is:

1. An earth auger including in combination, a semi-cylindrical member of a circumference approximately 216 degrees having an extending dished sector-shaped cutter blade continued from one longitudinal edge of said member and ending at a point marking the center of said cylindrical member, an obliquely extending flange of gradually decreasing width starting from the other longitudinal edge of said member, an access opening being formed between said flange and

blade and said longitudinal edge bulging outwardly at its union with said blade, and a spanner having a handle socket secured 25 to said cylindrical member at the end opposite of said flange and blade.

2. An earth auger including in combination, a semi-cylindrical member from one edge of which extends a dished sector shaped 30 cutting blade with an adjacent obliquely extending flange of gradually decreasing width extending from the opposite edge, an access opening being formed between said flange and blade, and a handle secured to 35 said cylindrical member.

In testimony whereof we affix our signatures, in presence of two witnesses.

BENJAMIN G. WATKINS.

WALTER P. WATKINS.

TAYLOR WATKINS.
